No. 37,408.

Patented April 18, 1905.

UNITED STATES PATENT OFFICE.

OSCAR S. STRAUS, OF NEW YORK, N. Y., ASSIGNOR TO L. STRAUS & SONS,
OF NEW YORK, N. Y.

DESIGN FOR A DISH.

SPECIFICATION forming part of Design No. 37,408, dated April 18, 1905.

Application filed March 25, 1905. Serial No. 252,080. Term of patent 14 years.

To all whom it may concern:

Be it known that I, OSCAR S. STRAUS, a citizen of the United States, residing in the city of New York, in the borough of Manhattan and State of New York, have invented a new, original, and ornamental Design for Dishes, the same being disclosed in the accompanying drawings, in which—

I claim—

The ornamental design for a dish, as shown.
OSCAR S. STRAUS.
